UNITED STATES PATENT OFFICE.

WILLIAM R. MARSHALL, OF HOLYOKE, MASSACHUSETTS, ASSIGNOR TO THE HOLYOKE COMPANY, OF HOLYOKE, MASSACHUSETTS, A CORPORATION OF NEW YORK.

WINDING SPOOL.

Application filed August 9, 1921. Serial No. 490,948.

To all whom it may concern:

Be it known that I, WILLIAM R. MARSHALL, citizen of the United States, residing at Holyoke, in the county of Hampden and State of Massachusetts, have invented new and useful Improvements in Winding Spools, of which the following is a specification.

The present invention relates to winding 10 spools or reels and more particularly to a spool or reel which is adapted for use in a winding machine for holding a coil of wire while it is being wound, and which is adapted to permit the coil, in its completed form 15 to be bodily removed from the spool. The spool herein illustrated is furthermore so constructed and arranged that, before the coil is removed, the turns of wire may be tied together in several places by cross 20 strands of binding material to form a package suitable for shipment.

Coils of wire, tied as above described, are sold to manufacturers who employ them for supplying wire to machines in which it is 25 used in the manufacture of various articles. It is customary to produce such coils by winding a continuous strand of wire upon a core of slightly conical or tapering core in order that the coil, after being wound, may 30 be bodily removed from the small end of the core with facility. The coils are of substantial width, however, and when wound upon a tapering core, the coil itself is of slightly conical form, i. e., one end of the 35 coil is of somewhat greater diameter than the opposite end. Tapering coils are objectionable since in unwinding the wire therefrom, the turns of wire adjacent the large end of the coil tend to fall down and 40 overlap the strand which is being unwound and thus are liable to become tangled therewith so as to interfere with the delivery of the wire.

It is also customary to wind wire upon 45 solid wooden spools having cylindrical cores. In this way so called "level" coils, or coils of true cylindrical shape may be produced, but the coils cannot be removed from the solid spools without being unwound and 50 therefore it is necessary to sell the spools with the coils.

One object of the present invention is to provide an improved winding spool or reel upon which a "level" or cylindrical coil 55 may be wound and from which the coil

may be bodily removed with facility after being completed.

To the accomplishment of the above object and such others as may hereinafter appear, the invention consists in the features 60 of construction and the combinations and arrangements of parts hereinafter described and claimed, the advantages of which will be obvious to those skilled in the art.

The invention will be readily understood 65 from the following description, reference being had to the accompanying drawings illustrating the preferred embodiment thereof.

In the drawings;—

Fig. 1 is a longitudinal, sectional view 70 of a winding spool, constructed in accordance with the present invention, the spool being secured in position upon the winding arbor of a winding machine;

Fig. 2 is a sectional view taken on the 75 line 2—2 of Fig. 1;

Fig. 3 is a perspective view of the winding spool shown in Fig. 1, one of the spool heads being detached from the core;

Fig. 4 is a view, in side elevation and on a reduced scale, of the winding spool showing one of the spool heads detached and the core collapsed preparatory to removing a 80 coil of wire therefrom; and

Fig. 5 is a perspective view of a coil of 85 wire ready for shipment.

As shown in the drawings, the improved winding spool or reel comprises a hollow cylindrical core or central portion 6, and the spool heads or flanges 7 and 8 which 90 constitute the opposite ends of the spool, the spool head 8 being detachable from the core to permit the removal of the coil from the spool. To further facilitate the removal of the coil, the core 6 is adapted to collapse 95 from the cylindrical form shown in Fig. 1 to the slightly tapering form shown in Fig. 4. To this end, the core 6 is composed of

a plurality of separate longitudinal sections 9 which are severally pivoted adjacent 100 one end, to the spool head 7. In the present instance the core is composed of three sections although the invention is entirely independent of the number of core sections employed.

The spool head 7 consists of a disk having a hub 10 extending outwardly therefrom. As best shown in Fig. 3, the hub 10 is conveniently formed with three radial projections 11 which are apertured, as in 110

dicated at 12, to receive the ends of the core sections 9, and the latter are mounted upon transverse pivot pins 13, the opposite extremities of which are fixedly secured in 5 the radial hub projections 11. As shown, the pivoted ends of the core sections are considerably reduced in width, to facilitate the pivotal mounting of the same in the manner described. The hub 10 is also centrally 10 apertured to fit closely upon a winding arbor 14 which extends through the collapsible core 6 and through the detachable spool head 8.

The detachable spool head 8 consists of a 15 disk having a slightly tapered hub 15 which is apertured to fit the winding arbor 14 and which is adapted to project between the adjacent ends of the core sections 9 to swing the latter apart sufficiently to maintain the 20 sides of the core in parallel relation to the winding arbor so that a cylindrical winding surface will be formed.

The component parts of the winding spool are held in assembled relation upon 25 the winding arbor by means of a nut 17 which is threaded upon the outer end of the arbor. The nut 17 binds the detachable spool head 8 against the adjacent end of the core and also rigidly secures the 30 spool to the arbor by binding it tightly between the nut 17 and a collar 18 that is fixed upon the arbor. When the parts are thus assembled, the courses of wire successively wound upon the spool will be level and consequently the coil will be perfectly cylindrical in shape.

After a coil has been wound upon the spool and before it is removed therefrom, the turns of wire in the coil are tied together 40 by means of cross strands of wire or other binding material, so as to firmly hold the coil in shape during shipment. In the present device provision is made whereby the binding strands may be applied to the 45 coil before the coil is removed from the spool. To this end, the spool heads 7 and 8 are each provided with three radial slots 20 which extend from the peripheries of the spool heads nearly to the central apertures therein. 50 The slots 20 in the spool head 7 are arranged in radial alinement with the spaces between the core sections and said slots communicate with said spaces, as shown clearly in Fig. 2. The slots 20 in the spool head 8 are maintained in a similar relation to the spaces between the core sections by means of a dowel pin 22 in the spool head 8 which enters a notch 24 in the adjacent end of one of the core sections. Before the spool head 8 is disassembled 55 from the rest of the spool, short strands of wire are inserted longitudinally through the rear extremities of the radial slots 20 in one of the spool heads and these strands of wire are projected through the spaces between the core sections, as indicated by the

dotted line 26 in Fig. 1, until they emerge through the slots 20 in the opposite spool head. These strands of binding wire are then wrapped around the coil, as indicated in Fig. 5, and their opposite ends are twisted 70 together to securely bind together the courses of wire in the coil. After the coil is thus tied, the detachable spool head 8 is removed to permit the core to collapse so that the coil may be removed therefrom. 75

To permit the removal of the spool head 8, the nut 17 is unscrewed from the winding arbor 14. The three core sections 9, then being unsupported by the hub of the spool head 8, will collapse slightly, as shown in 80 Fig. 4, so that the core will then be of somewhat tapering form. The coil of wire may then be readily removed from the core.

To permit the above-described collapse of the core sections, a slight clearance space is 85 provided, as shown, between both the outer and inner sides of the core sections and the corresponding walls of the apertures 12 in the hub of the spool head 7. To insure that the collapse of the core will be effective to 90 quickly release the portion of the coil immediately adjacent the spool head 7, the pivot pins 13 are located a substantial distance outside of the winding space between the spool heads. Consequently as the core 95 sections swing inwardly toward the winding arbor they will move out of engagement with the inner periphery of the coil at the portions immediately adjacent the spool head 7, as well as throughout the rest of the width of 100 the coil. The unpivoted ends of core sections are adapted to fit into an annular groove 28 in the inner face of the spool head 8, adjacent the exterior of the hub 15. With this construction the outer wall of the groove 105 20 serves as a stop shoulder to limit the outward movement of the core sections 9. Furthermore, there is no danger of the strands 110 of wire becoming wedged between the end of the core and the spool head 8 while the first 115 courses of the coil are being wound.

After the removal of the coil from the spool, the core 6 may be again expanded so as to restore it to normal cylindrical form ready for the winding thereon of another 115 coil, by replacing the spool head 8 upon the winding arbor with its hub 15 projecting between the free ends of the core sections, and locking said spool head to the arbor and to the rest of the spool by means of the nut 17. 120

It will be seen that the use of the present winding spool insures that the courses of wire successively laid as a coil is built up will be perfectly level, and consequently that the coil, when completed, will be of a true cylindrical shape. Thus, when the wire is unwound from the coil in the machine in which it is to be used, there is no danger of the strands of wire becoming tangled or the uniform feed of the wire being interfered with. 125 130

The use of the present device also does away with the desirability of employing solid wooden spools for retaining the coils of wire in shape. As a result, the time spent in handling such spools is saved. Also the expense due to the breaking of the wooden spools and to the tying up of large quantities of spools is eliminated.

While it is preferred to employ the specific arrangement of parts shown and described, it will be understood that such construction and arrangement is not essential except so far as defined in the claims and may be changed or modified without departing from the spirit of the invention.

What is claimed is:—

Claims:

1. A winding spool having in combination a pair of spool heads, a collapsible core comprising a plurality of longitudinal sections severally pivoted to one of the spool heads for swinging adjustment in axial planes to contract or expand the core, said core sections being severally constructed and relatively arranged when the core is expanded to provide an approximately continuous cylindrical winding surface upon which a coil may be wound in true cylindrical shape, one of said spool heads being detachable from the core to permit the coil to be bodily removed from the core when the core is collapsed, and means on the detachable spool head for limiting the expansion of the core. 90
2. A winding spool having, in combination, a pair of spool heads, a collapsible core comprising a plurality of sections severally pivoted to one of the spool heads, said core sections being constructed and adapted to be normally positioned in closely adjacent relation to provide an approximately continuous cylindrical winding surface upon which a coil may be wound in true cylindrical shape, one of said spool heads being detachable from the core and so constructed and arranged that when assembled therewith it will locate and lock the core sections in their normal positions and when detached therefrom it will permit the collapse of the core to facilitate the removal of the coil bodily therefrom. 100
3. A winding spool comprising a member constituting one end of the spool, a core consisting of a plurality of separated longitudinal sections pivoted at one end to said member for swinging movements in axial planes, a second member adapted to be detachably secured to the core to constitute the other end of the spool, means on said second member for limiting the outward movements of the core sections to relatively position them so as to present a cylindrical winding surface and rigid means for supporting the sections of the core in engagement with said limiting means. 110
4. A winding spool comprising a spool head centrally apertured to receive a winding arbor, a collapsible core adapted to enclose the arbor and comprising a plurality of separated longitudinal sections severally constructed and relatively arranged when expanded to provide a substantially continuous cylindrical winding core, each of said sections having reduced extremities severally pivoted to said spool head to adapt the sections for swinging movements in axial planes to collapse or expand the core, a second spool head centrally apertured to receive the winding arbor and adapted to be detachably secured to the core, a hollow hub carried by the second spool head having a conical exterior adapted to project within the core to spread apart the core sections and to support them during the winding operation in position to present a cylindrical winding surface, the spool heads adapted to be clamped between means on the winding arbor for the purpose of holding the parts of the spool in assembled relation with the core expanded and for securing the assembled spool to the arbor. 120
5. A winding spool having, in combination, a spool head, a collapsible core comprising a plurality of separated longitudinal sections severally pivoted at one end to said head for swinging movements in axial planes, a second spool head adapted to be detachably secured to the core, the second spool head having an annular groove in its inner face and a tapering hub upon its inner side, said groove being adapted to receive the free ends of the core sections to locate and maintain said sections in parallel relation with the axis of the spool and the exterior of the hub constituting the inner side wall of said groove and being adapted to be projected between the free ends of the core sections when the spool is being assembled to guide said ends into said groove. 130
6. A winding spool, having, in combination, a spool head, a hollow collapsible core comprising a plurality of longitudinal sections normally separated throughout their length by open spaces and severally pivoted at one end to said head for movements in axial planes, a second spool head adapted to be detachably secured to the other ends of the core sections and to maintain the core in expanded condition, the first spool head having a plurality of radial slots extending from its periphery to points included within the peripheral plane of the expanded core and arranged to communicate with the spaces between the core sections and the second spool head having a similar series of slots therein, and cooperating means on the core and the second spool head for locating said head radially with respect to the core to bring its slots also into communication with said spaces. 140
7. A winding spool comprising a collapsi-

ble core normally expanded to provide a cylindrical winding surface, members associated with the core to constitute the opposite ends of the spool, one of said members being detachable from the core to permit a coil wound upon the latter to be bodily removed therefrom when the core is collapsed and said detachable member having means for insuring that said core will be expanded when said member and core are assembled, and means for preventing relative rotation of the core and said detachable member.

8. A winding spool comprising a member constituting one end of the spool, a core consisting of a plurality of separated longitudinal sections pivoted at one end to said

member for swinging movements in axial planes, a second member adapted to be detachably secured to the core to constitute the other end of the spool, means on said second member for limiting the outward movements of the core sections to relatively position them so as to present a cylindrical winding surface, means rendered effective to expand said core by the act of assembling said second member with said core, said means serving to support said core in expanded condition with the unpivoted ends of the core sections in engagement with said limiting means.

In testimony whereof I have affixed my signature.

WILLIAM R. MARSHALL.
